UNITED STATES PATENT OFFICE.

CHARLES E. JOHNSON, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

1,111,387.

Specification of Letters Patent.

Patented Sept. 22, 1914.

Application filed July 15, 1913. Serial No. 779,112.

To all whom it may concern:

Be it known that I, CHARLES E. JOHNSON, a citizen of the United States, and a resident of New Britain, in the county of Hartford and State of Connecticut, have invented a new and Improved Lock, of which the following is a specification.

My invention relates more especially to that class of locks known as permutation locks, and an object of my invention, among others, is to provide a lock of this class that shall be extremely simple and cheap in construction, and one in which the changes in the combination may be easily effected.

One form of lock embodying my invention and in the construction and use of which the objects herein set out, as well as others, may be attained, is illustrated in the accompanying drawings, in which—

Figure 1 is a front face view of the door of a post office box provided with my improved lock and illustrating the position of certain pins to locate the tumblers to permit the throwing of the bolt. Fig. 2 is a rear face view of the lock with the back plate partially broken away to show construction of the bolt throwing plate, the tumblers being in position to permit movement of the bolt throwing plate. Fig. 3 is a like view with the back plate and bolt throwing plate partially broken away to show the mounting for the tumblers. Fig. 4 is a rear face view with several of the plates broken away to show the construction and operation of the resetting plate and lever. Fig. 5 is a top edge view of the door illustrating the operation of the resetting lever, the resetting stud being shown in dotted outline.

While my invention is not limited to any particular form of lock, yet as it is especially applicable in that class of locks used on the lock boxes commonly employed in post offices, I have selected such for the purpose of disclosure of my invention herein.

In the accompanying drawing, the numeral 10 denotes a door frame and 11 a door pivotally mounted therein to close the opening therethrough. A bolt 12 is mounted in any suitable manner upon the back of the door to engage a recess or keeper 13 in the door frame, as herein shown this bolt being mounted in loops 14 fastened to the back of the door.

Lugs 15 project from the back face of the door, between which lugs the different plates comprised in the lock mechanism are movably located. Pin openings 16 are formed through the door for the reception of pins projecting from the tumblers. A resetting lever 17 is pivotally mounted in a recess in the back face of the door, this lever having a stud 18 projecting into a hole in a resetting plate 19, and a resetting arm 20 projects from the lever in position to engage a resetting and bolt plate actuating stud 21 projecting from a wall of the opening through the door frame. This resetting plate is so mounted between the lugs 15 that it has a sliding movement lengthwise of the door, this sliding movement being caused by the operation of the resetting lever 17, the stud 18 being so loosely engaged within the hole in the resetting plate as to permit this action. This resetting plate is also provided with openings 22 through which pins from the tumblers project. These openings are so formed that when any of the tumblers have been moved into position to permit movement of the bolt throwing plate, upon movement of the resetting plate the pins will be so engaged as to move the tumblers into locked position. Guide studs 23 projecting through slots in the resetting plate may be employed to facilitate this sliding movement.

A tumbler plate 24 is mounted between the lugs 15, resting upon the resetting plate, this tumbler plate being held against movement between said lugs. It is provided with tumbler slots 25 in which tumblers 26 are slidably located, each tumbler having a pin 27 projecting through the pin openings in the resetting plate and through the door where they are accessible at the front of the door for the purpose of operating the tumblers to place them in position to permit movement of the bolt throwing plate. Each tumbler is provided with a locking stud 28 so arranged that it may control the movement of a bolt throwing plate 29. This bolt throwing plate is mounted upon the tumbler plate and between the lugs 15, having a sliding movement crosswise of the door between said lugs. A spring 30 is properly engaged with the bolt throwing plate to move it backwardly, and this plate has a finger 31 positioned to engage a finger 32 on the bolt 12 for the purpose of mov-

ing the latter, a spring 33 being interposed between a projection from the bolt throwing plate and the bolt to move the latter into its keeper recess, as shown, this spring 5 thrusting against the finger 32 on the bolt.

The parts are so constructed that each of the locking studs upon the tumblers may be arranged to register with a releasing recess 34 in the bolt throwing plate, whereby 10 any one or more of the tumblers may be moved to register its locking stud with a releasing recess. In use the parts will be so arranged that the locking studs on a number of the tumblers will normally register with their coöperating releasing recesses, and these tumblers, when the parts are so arranged, are termed as "dead" tumblers. The parts will be so arranged that the remainder of the tumblers must be moved to 15 cause their studs to register with the releasing recesses, and when so arranged these tumblers are termed "live" tumblers. From this construction it will be seen that the "live" tumblers must be moved to enable 20 the lock to be operated, but if a "dead" tumbler be moved it will so position its stud that the lock cannot be operated. For the purpose of description the tumblers *a*, *b*, *c*, *d*, and *e* are shown herein as "live" tumblers 25 and are the ones to be moved to enable the lock to be operated.

In order to enable each of the tumblers to act as a "dead" or "live" tumbler it is necessary that the location of the releasing 30 recesses and the studs may be changed one with respect to another, and I have provided means in my improved lock whereby this change may be readily made in a simple manner and without requiring the lock to 35 be taken apart. In effecting this result the bolt throwing plate is provided with a number of locking stud recesses 35 within which the studs may move when the tumblers are moved lengthwise of the door, and the releasing recesses 34 in the plates 36 carried 40 by the plate 29 open out of these locking stud recesses. A releasing recess plate 36 is removably inserted in a releasing recess plate opening 37 appurtenant to each of the tumblers, each plate having a releasing recess 34 so located that a tumbler may be 45 moved to cause its locking stud to register with said recesses, or locking studs and recesses may be registered when the tumblers are in their normal positions. For this purpose each recess plate is made reversible so that its releasing recess may be located at 50 either end of its coöperating locking stud recess, and as a ready means for removing 55 and arranging the releasing recess plates a threaded opening 38 is formed in each plate within which a threaded stud may be removably secured for the purpose of removing the plate.

60 In the construction herein shown it will

be noted that the plates *a*, *b*, *c*, *d*, and *e*, (these letters being applied and referring to both the tumblers and their pins, as also to the releasing recess plates, for the sake of clearness) are in position to register with locking studs on "live" tumblers when moved into interlocking position. 70

In the operation of the device the tumblers *a*, *b*, *c*, *d*, and *e* are first moved to cause 75 their locking studs to register with the releasing recesses. As soon as the last stud is moved into registering position with its recess the spring 33 will move the bolt throwing plate 29 backward, the fingers 31 and 32 engaging to move the bolt 12 from engagement with its keeper, thereby unlocking the door. As the door is swung open a cam plate 39 projecting from the bolt throwing plate engages the stud 21,

throwing the bolt plate forward, which movement, through the medium of the spring 33, also moves the bolt 12 forward. In the continued opening movement of the door the resetting arm 20 engages the opposite side of the stud 21, and swings the re- 80

setting lever 17 on its pivot, moving the resetting plate so that the edges of the openings therein will engage the pins on all of the live tumblers and move them back to their normally locked positions, which 85

movement is permitted by reason of the fact that the bolt throwing plate has been just moved to allow this result. As the door, after having been opened, is now closed the bolt 12 will be sprung backward in the usual 90

manner against the force of the spring 33 which latter will immediately move the bolt into engagement with its keeper recess, thus locking the door in its closed position. In this closing movement of the door the lever 100 20 will yieldingly pass the pin 21, this yielding movement and the consequent movement of the resetting plate, however, having no effect upon the tumblers which have just been moved to their normal position. As 105

the closing of the door is effected a pin 40 will finally engage the lever 20 and move it back to its normal position, it being noted that the movement of the lever 20 is thus 110 effected without the employment of springs. 115

While I have shown and described herein a preferred form of mechanism for effecting my purpose, this may be departed from to a greater or lesser degree and yet be within the spirit and intent of the invention, which 120 is therefore not limited to the exact construction herein shown and described.

I claim—

1. In combination with a door or like part, a lock mounted thereon and including 125 tumblers as a part of the lock mechanism, a resetting plate for operating the tumblers, a lever pivotally mounted with one end loosely connected with the resetting plate and the opposite end located to engage an 130

operating member to move the lever, and the operating member located in the path of movement of said lever.

2. In combination with a door or like part, a lock mounted thereon and including tumblers as a part of the lock mechanism, a resetting plate to operate the tumblers, a bell crank lever pivotally secured to the door underneath the resetting plate with one arm located against the side of and loosely attached to said plate and the other arm bent at an angle to pass through the door opening, and a resetting member located on the door frame in the path of movement of said lever.

3. In combination with a door or like part, a lock mounted thereon and including a movably mounted bolt throwing plate, a bolt connected therewith, a movably mounted resetting plate, tumblers connected to be operated by said resetting plate, a cam plate projecting from the bolt throwing plate, a resetting lever connected with the resetting plate, and a stud located in the path of movement of said cam plate and said resetting lever to actuate them.

4. In combination in a lock including a bolt, a tumbler plate, tumblers movably mounted in recesses in said plate, a bolt throwing plate resting against the tumbler plate and holding said tumblers in place, said bolt throwing plate being operatively connected with said bolt and carrying members having locking stud recesses and releasing recesses, and means to permit independent change of the releasing recesses with respect to the tumblers.

5. In combination in a lock including a bolt and tumblers to permit operation of the bolt, a bolt throwing plate located to cover said tumblers, operatively connected with said bolt and carrying members having locking stud recesses and releasing recesses, and means to permit independent change of the position of the releasing recesses with respect to the tumblers.

6. In combination with a lock including a bolt and tumblers to permit operation of the bolt, a bolt throwing plate operatively connected with said bolt and having locking stud recesses and releasing recesses, and means removably secured to the bolt throwing plate for changing the relative position of the releasing recesses with respect to the tumblers.

7. In combination with a lock including a bolt and tumblers to permit operation of the bolt, a bolt throwing plate operatively connected with said bolt and having locking stud recesses therein, a member detachably secured to said plate and having releasing recesses, and means to permit change of the position of the releasing recesses with respect to the tumblers.

8. In combination in a lock, including a

bolt and tumblers to permit operation of the bolt, a bolt throwing plate operatively connected with the bolt, releasing recess plates detachably secured to the bolt throwing plate, and means to permit change of the position of the recess plates to change the position of the releasing recesses with respect to the tumblers.

9. In combination in a lock including a bolt and tumblers to permit operation of the bolt, a bolt throwing plate operatively connected with said bolt, recess plates removably secured to the bolt throwing plate, said bolt throwing plate having angular recesses located therein, and means to permit change of the position of the recess plates to alter the position of said angular recess with respect to a tumbler.

10. In combination in a lock including a bolt and tumblers to permit operation of the bolt, a bolt throwing plate operatively connected with the bolt and having locking stud recesses therein, and reversible releasing recess plates located in openings in the bolt throwing plate and having releasing recesses.

11. In combination in a lock including a bolt and tumblers to permit operation of the bolt and a resetting plate to return the tumblers to their normal positions, a lever operatively connected with the resetting plate, a stud to positively move the lever in one direction, and a pin to positively move it in the opposite direction.

12. In combination in a lock including a bolt and tumblers to permit operation of the bolt, a resetting plate to return the tumblers to their normal positions, said resetting plate having pin slots, pins projecting from the tumblers through said slots, said resetting plate being movable to replace the pins in their normal positions, a pivotally mounted lever having one end in engagement with the resetting plate and the opposite end projecting into the path of movement of a resetting stud, and the resetting stud.

13. In combination in a lock including a bolt and tumblers to permit operation of the bolt, a plate operatively connected with said bolt and having recess plate openings and smaller locking stud recesses opening therethrough, and recess plates removably located in said openings and having releasing recesses opening to the edge of the plate into said locking stud recesses.

14. In combination in a lock including a bolt with tumblers to permit operation of the bolt, a member operatively connected with said bolt and having locking stud recesses therein, and a member detachably secured to said first mentioned member and having releasing recesses, said last mentioned member being arranged to change the position of its releasing recesses with respect to the tumblers.

15. In combination in a lock including a bolt and tumblers to permit operation of the bolt, a bolt throwing plate operatively connected with said bolt and having openings therein, and recess plates removably located in said openings and arranged to change the position of the recesses therein with respect to the tumblers.
16. In combination in a lock including a bolt and tumblers to permit operation of the

bolt, a member operatively connected with said bolt and carrying members having angular shaped recesses therein to receive projections from the tumblers, and means for independently reversing the position of each of said recesses.

CHARLES E. JOHNSON.
